UNITED STATES PATENT OFFICE.

EDWIN A. ROSS, OF VENICE, CALIFORNIA.

DENTAL-FLOSS HOLDER.

1,316,807.

Specification of Letters Patent. Patented Sept. 23, 1919.

Application filed May 2, 1917. Serial No. 165,964.

To all whom it may concern:

Be it known that I, EDWIN A. ROSS, a citizen of the United States, residing at Venice, in the county of Los Angeles and 5 State of California, have invented new and useful Improvements in Dental-Floss Holders, of which the following is a specification.

My invention relates to dental floss holders and consists in the novel features herein 10 shown, described and claimed.

Figure 1 is a side elevation illustrating the device with parts broken away to more clearly disclose the tension mechanism.

Fig. 2 is a side elevation at right angles to 15 Fig. 1 and disclosing the general design of the holder and its handle.

Fig. 3 is an enlarged view in perspective illustrating the pin by which the floss is secured to the tension rod.

20 Fig. 4 is an enlarged sectional detail on the line 4—4 of Fig. 1.

Referring more particularly to the drawings, 10 indicates the base of a dental floss holder which is here shown as formed with 25 a central bore 11 within which a tubular floss holder 12 extends. This floss holder is exteriorly threaded to engage threads within a bore 13 formed the length of the handle 14. A central opening extends the length 30 of the floss holder and is adapted to receive a spool of floss 15. It is to be noted that the threads of the floss holder do not engage the bore of the base. Formed integral with the end of the floss holder is a tension rod 35 16 which extends along an extension bore of reduced diameter in the neck 17 of the holder. A fastening pin 18 is formed at the end of the tension rod and extends upwardly through a slot 19 in the holder neck. The 40 exact configuration of this pin is more clearly shown in Fig. 3 where it will be seen that it has an arcuate groove 20 formed across its head. This groove is bounded on one side by an elevated portion 21 of the 45 head which permits the floss to be easily caught and placed in the groove. Formed integral with the base and at the end of the neck is a fork having prongs 22 and 23. These prongs extend outwardly and are 50 fitted with grooves 24 in their ends to receive the strand of floss and to hold a portion of it taut, as indicated by the numeral 25 in Fig. 1. In order to permit the floss holder to slide within the base without ro- 55 tating, a lug 26 is formed within the bore of

the base and extends into a groove which is formed the length of the floss holder.

In operation a spool of floss is placed within the bore of the floss holder and the end of the floss is passed out through an 60 opening in the end of the floss holder. This thread is drawn out through the slot 19 in the neck of the bore and thereafter unwound from the floss spool so that it will be of a length sufficient to pass around the fork and 65 back to the pin 18. The floss is then positioned in the slot 20 of the pin and wrapped around the body of the pin several times, then it is led over the prong 22 across the end of the fork and from the prong 23 70 to the pin again. Here it is drawn through the groove in the head of the pin and thereafter wound several times around it. The handle 14 is then rotated in a clockwise direction and, due to the fact that the thread 75 upon the bobbin and within the handle is left-handed, the bobbin will be retracted. This will cause the pin 18 to be drawn along the slot 19 and away from the fork and as the floss has been fixed by wrapping around 80 the pin, the floss 25 will be drawn very tight, thus permitting it to be conveniently used.

It will thus be seen that the device here disclosed is simple and compact in its design and provides a floss holder and container which will permit the floss to be withdrawn from the container and tensioned 85 upon the holder.

While I have shown the preferred form 90 of my dental floss holder as now known to me, it will be understood that various changes in the combination, construction and arrangement of parts may be made by those skilled in the art without departing from the spirit of my invention. 95

I claim:

1. In a dental floss holder, a handle having an internal screw-thread from one end, a floss holder screw-seated in the handle and extending from the end of the handle and 100 having a longitudinal central opening, a base having a bore from one end to receive the floss holder and an extension bore extending from the first bore and a slot communicating with the extension bore; said 105 end of the base fitting against the end of the handle; a floss spool mounted in the floss holder, a tension rod extending from the end of the floss holder into the extension bore, a fastening pin at the opposite end 110

of the tension rod from the floss holder and extending through the slot in the base, and a fork extending from the opposite end of the base from the handle.

5. 2. In a dental floss holder, a handle having an internal screw-thread from one end, a floss holder screw-seated in the handle and extending from the end of the handle and having a longitudinal central opening, a 10 base having a bore from one end to receive the floss holder and an extension bore extending from the first bore and a slot communicating with the extension bore; said end of the base fitting against the end of the handle; a floss spool mounted in the floss 15

holder, a tension rod extending from the end of the floss holder into the extension bore, a fastening pin at the opposite end of the tension rod from the floss holder and extending through the slot in the base, a fork 20 extending from the opposite end of the base from the handle, and dental floss wound upon the floss spool and extending out of the floss holder and through the slot and passing around the ends of the fork and 25 back to and attached to the fastening pin.

In testimony whereof I have signed my name to this specification.

EDWIN A. ROSS.
